UNITED STATES PATENT OFFICE.

GEORGE L. LYON, OF ALBANY, NEW YORK.

ICE-CREEPER.

SPECIFICATION forming part of Letters Patent No. 288,647, dated November 20, 1883.

Application filed July 5, 1883. (No model.)

To all whom it may concern:

Be it known that I, GEORGE L. LYON, of the city and county of Albany, in the State of New York, have invented certain new and useful Improvements in Ice-Creepers, of which the following is a specification.

My invention relates to improvements in the class of ice-creepers that are detachable from the boot or shoe; and the object of my invention is to provide a simple, cheap, and effective device that may be readily attached to and detached from the heel of a boot or shoe, and afford to the wearer the required protection against slipping while walking on ice. I attain this object by means of the construction illustrated in the accompanying drawings, which form part of this specification, and in which—

Figure 1 is a plan view of a shoe-heel with the fastening-plate secured thereto; Fig. 2, a plan view of a spur-piece detached from the heel; Fig. 3, a side elevation of same; Fig. 4, a vertical section of the fastening-plate at the line *x x* on Fig. 1; Fig. 5, a perspective view 15 of the heel of a shoe with the creeper attached thereto, and Fig. 6 a modification of my device as adapted to india-rubber shoes.

As represented in the drawings, A is the heel of a boot or shoe; B, the fastening-plate, 20 and C the spur-piece, of the ice-creeper.

The fastening-plate B, I preferably make in the form of a circular disk, so as to facilitate the operation of attaching it to a heel, into the bottom of which the said fastening-plate should 25 be inserted, so as to lie flush with the surface of the heel, and there secured by means of screws or nails, as shown in Fig. 1. The said fastening-plate contains a recess, *b*, in its upper side, and a slot, *b'*, leading thereinto, is 30 formed for receiving the T-head of a spur-piece in the manner hereinafter described. A second slot, *b''*, narrower than the slot *b'*, crosses the latter at an acute angle, and is made for the purpose of facilitating the removal of 35 dirt or other obstructive matter that may collect in the recess *b*. By means of the slots *b'* and *b''* oppositely-located points *b'* are formed, and the inner faces of said points are provided 40 with an incline or spiral twist, as shown in Fig. 4, for the purpose of drawing the spur-

piece in close contact with the fastening-plate, as hereinafter described.

The spur-piece C is provided on its under side with sharp spurs *c*, for producing the required hold on icy surfaces, and on its upper side a T-head, *c'*, is formed. The bar of said T-head is adapted to enter into the slot *b'* of the fastening-plate, and its projecting arms are adapted to engage with the upper faces of the points *b'* of said fastening-plate in such manner that the spur-piece will be securely clamped in place. The spur-piece C is also provided with an arm, *c''*, which projects toward the front of the heel, as shown in Fig. 5, and to the outer end of said arm a spring, *c'*, is pivoted. In the free end of said spring there is an opening or loop that is adapted to engage over a stud, D, fixed in the breast of the heel, as shown in Figs. 1 and 5.

The mode of attaching the spur-piece to the fastening-plate is as follows: The said spur-piece is turned to one side, as indicated by the dotted lines in Fig. 1, so as to permit the T-head *c'* to enter the slot *b'* of the fastening-plate. When the said T-head is fully inserted 70 in the slot *b'*, the spur-piece is turned back to bring the arm *c''* toward the middle of the front side of the heel. By this movement the spiral faces of the points *b'*, by bearing against the projecting arms of the T-head *c'*, will draw 75 down the spur-piece C into close contact with the bottom of the heel A. The spring *c'* is then fixed over the stud D, and thereby the spur-piece C will be securely locked in place. The spur-piece can be removed from the heel 80 in a moment, by simply reversing the operation just described.

Instead of attaching the spring *c'* to the arm *c''*, as above described, it will readily be seen that said spring may be attached to a stud 90 fixed in the breast of the heel, and thus be adapted to engage with a pin formed on the end of the arm *c''*, thereby reversing the mode of using the spring *c'*, above described. Again, instead of forming the spring *c'* to engage over 95 a stud D, as herein shown and described, the said spring attached to the arm *c''* may be constructed to hook over one edge of the heel A. In fact, the mode of locking the spur-piece C in place, after it is engaged with the fastening- 100

plate B, as described, admits of an almost end-less variety of changes.

In the modified form applicable to india-rubber shoes, as shown in Fig. 6, the fastening-plate B is provided with wings b^4 and an arm, b^5 , as indicated by the dotted lines in said figure. The said fastening-plate is embedded in the rubber heel and secured by rivets in such manner that only the circular face 10 of the plate and the end of the arm b^5 will be exposed. The end of the arm b^5 serves to receive the end of the spring c^3 of the spur-piece C in the same manner that the stud D does, and the mode of attaching the spur-piece 15 to the fastening-plate is the same in every respect, as hereinbefore described.

I claim as my invention—

1. As an improvement in ice-crawlers, the

combination, with the fastening-plate B, provided with a slot, b' , and adapted to be secured in the heel of a boot or shoe, as described, of the spur-piece C, provided with a T-head, c' , adapted to engage with the fastening-plate B, as set forth, and means, substantially as described, for locking the said spur-piece to its 25 place on the heel, as specified.

2. The fastening-plate B, provided with a slot, b' , wings b^4 , and arm b^5 , as herein set forth, in combination with the spur-piece C, constructed as herein described, and adapted 30 to engage with said fastening-plate in the manner and for the purpose herein specified.

GEORGE L. LYON.
